UNITED STATES PATENT OFFICE.

JAMES H. BUTLER, OF SOMERVILLE, MASSACHUSETTS.

DESIGN FOR A SCHOOL-CHAIR.

SPECIFICATION forming part of **Design No. 25,582**, dated June 2, 1896.

Application filed April 24, 1896. Serial No. 588,978. Term of patent 31 years.

To all whom it may concern:

- Be it known that I, JAMES H. BUTLER, a citizen of the United States, residing at Somerville, in the county of Middlesex and State 5 of Massachusetts, have invented and produced a new and original Design for School-Chairs; and I do declare the following to be a full, clear, and exact description of the same, reference being had to the accompanying drawings, 10 forming a part thereof.
- Figure 1 is a top plan view of a school-chair, showing my design. Fig. 2 is a side elevation of the same; and Fig. 3 is a cross-section on the line 3 3 shown in Fig. 1.
- 15 Similar letters refer to similar parts wherever they occur on the different parts of the drawings.
- The leading feature of my design consists in a concave top piece or back-rest A, from 20 which extends downwardly the convex rounds B B to the seat C, and in combination with such concave back and convex rounds I have

shown curved arm-supports or side pieces D D, extending from the concave top piece A to the sides of the seat C, as fully illustrated 25 in the drawings.

By the combination of a concave top piece, convex rounds, and curved side pieces extending from said concave top piece to the seat a very artistic design for a school-chair is pro- 30

duced.

What I claim is—

The design for a school-chair herein shown and described, the same comprising a concave top or back support A, convex rounds 35 B extending from said concave top to the seat C and curved side pieces or arm-rests D, D, as herein set forth.

In testimony whereof I have affixed my signature in presence of two witnesses.

JAMES H. BUTLER.
